UNITED STATES PATENT OFFICE.

JOSEPH ZABIELSKI, OF CHICAGO, ILLINOIS.

SAFETY-POCKET.

1,080,314.

Specification of Letters Patent.

Patented Dec. 2, 1913.

Application filed May 10, 1913. Serial No. 766,705.

To all whom it may concern:

Be it known that I, JOSEPH ZABIELSKI, a citizen of the United States, and a resident of the city of Chicago, county of Cook, and 5 State of Illinois, have invented certain new and useful Improvements in Safety-Pockets, of which the following is a specification.

My invention relates to safety pockets and the object of this improvement is to 10 provide a simple and effective means for securely locking a garment pocket in closed position.

Other objects will appear hereinafter.

The invention consists in the combinations 15 and arrangements of parts hereinafter described and claimed.

The invention will be best understood by reference to the accompanying drawing forming a part of this specification, and in 20 which—

Figure 1 is a view of a fragmental portion of a garment equipped with a locking device embodying my invention, Fig. 2 is a section of the same taken on line 2—2 in 25 Fig. 1, and Figs. 3, 4 and 5 are fragmental views of the device illustrating steps in locking the pocket.

The preferred form of construction as 30 illustrated in the drawing comprises a garment 6, a fragment of which is shown, having a pocket comprising an inner side 7 and an outer side 8. At the top of the outer side 8 is an opening 9 which affords entrance to the pocket. Secured to the inner side 7 35 above the outer side 8 is a flap 10 adapted to close the opening 9 of the pocket. A second flap 11 is secured to the inner side 7 over the flap 10 and adapted to cover the locking mechanism.

40 In the arrangement of the pocket in the garment, wall 6 is slitted horizontally, flaps 10 and 11 passed through the slit and said flaps, wall 6 and inner side 7 are secured by the same stitchings above the pocket opening 9. The sides 7 and 8 are stitched at their vertical edges and lower horizontal edge to wall 6.

45 The pocket is shown as applied in the ordinary "patch" pocket construction but by slight modification it may be applied to all forms of pockets, as will be readily understood by those skilled in the art.

Secured to the outer side 8 of the pocket are a plurality of rings 12 adapted to pass 55 through button hole openings 13 in the flap

10 to lock the flap 10 over the opening 9 of the pocket. A strap 14 is adapted to pass through the rings 12 to prevent the flap 10 from being raised from the rings 12. At each end of flap 10 chains 15 and 16 are secured to the outer side 8. The chains 15 and 16 are adapted to pass through button hole eyes 17 in the strap 14 to prevent the strap from becoming disengaged from the rings 12. The chains 15 and 16 are provided with 60 rings 18 and 19, the ring 19 being slidably mounted on chain 16 and the ring 18 preventing ring 19 from passing off chain 16. From this arrangement it will be seen that opening 9 of the pocket will be securely 70 locked against unauthorized entrance.

To lock the pocket, the rings 12 are inserted through button hole openings 13 and strap 14 inserted through the rings 12 to prevent flap 10 from disengagement from 75 the rings 12. The chain 15 is passed through its button hole opening 17 at the time the pocket is made and secured to the portion 8 as already described. The chain 16 is secured to the portion 8 of the pocket 80 and the ring 19 slidably mounted on chain 16 substantially as indicated. To insert the chain 16 in its button hole opening 17 the ring 19 is passed over the end of strap 14 at the left hand side of Fig. 1 substantially 85 as indicated in Figs. 3 and 4 passing over the button hole opening 17 in said strap 14. The ring 18 is then passed through said button hole opening 17 from the rear side thereof to the front. The ring 19 is then 90 slipped off from said end of the strap 14 and allowed to drop as indicated in Fig. 1. This effectively locks the pocket as already described. When the pocket is in its unlocked condition the strap 14 is substantially 95 in the position indicated in Fig. 5 so that upon raising the flap 10 the opening 9 of the pocket will be exposed. After the pocket is fastened the ends of chains 15 and 16 may be passed under flap 10 through opening 100 9 into the pocket to be out of view. The flap 11 then covers the portions of the locking device.

105 While I have illustrated and described the preferred form of construction for carrying my invention into effect, this is capable of variation and modification without departing from the spirit of the invention. I, therefore, do not wish to be limited to the precise details of construction set forth, but 110

desire to avail myself of such variations and modifications as come within the scope of the appended claims.

Having described my invention what I claim as new and desire to secure by Letters Patent is:

1. In combination, a garment pocket; a flap covering the opening of said pocket; perforated members carried by said pocket 10 and extending through said flap; a strap locking said perforated members through said flap; a chain secured to said pocket and extending through said strap; a ring on the free end of said chain; a second chain 15 secured to said pocket and extending through said strap; a ring secured to said second chain, slidably mounted on said first chain and adapted to lock said chains together, and a supplemental flap covering said first 20 mentioned flap and the locking means, substantially as described.

2. In combination, a pocket; a flap covering the opening of said pocket; rings carried by said pocket and extending through said flap; a strap through said rings and 25 provided with perforations near its ends; two chains carried by said pocket and extending through the perforations in said strap; a ring secured to each chain, one of said rings being slidably mounted on one of 30 said chains; and a supplemental flap secured above said pocket covering said first mentioned flap and the means for locking the pocket, substantially as described.

In testimony whereof I have signed my 35 name to this specification in the presence of two subscribing witnesses.

JOSEPH ZABIELSKI.
